UNITED STATES PATENT OFFICE.

CAMILLE E. ROY, OF CHICAGO, ILLINOIS.

JEWELRY TRAY.

Application filed October 24, 1921. Serial No. 510,025.

To all whom it may concern:

Be it known that I, CAMILLE E. ROY, a citizen of the United States, and a resident of the city of Chicago, in the county of 5 Cook and State of Illinois, have invented new and useful Improvements in Jewelry Trays.

This invention relates to that class of trays which are commonly used by jewelers and salesmen, for the display of jewelry in 10 display windows and cases.

The chief object of the invention is to produce a tray of stamped metal which is light and at the same time economical.

15 The novel features and claims of my invention as hereinafter set forth can best be understood by reference to the accompanying drawings which form a part of this specification and in which:—

20 Figure 1 is a plan view in assembly.
Figure 2 is a view in elevation.

Figure 3 is a section taken along the line 3—3 of Figure 1.

25 Figure 4 is a plan view of the bottom showing modifications.

Figure 5 is a detail view of one of the partitions.

Figure 6 is a section taken along line 6—6 of Figure 4.

30 Like reference characters indicate like parts throughout the views.

As is shown in Figure 1, my invention consists mainly of a continuous metal frame 1, a wood insert 2 and a bottom 3. The 35 frame 1 is so constructed as to form a ridge 4, an inwardly projecting shoulder 5, a downwardly projecting wall 6, and an inwardly projecting flange 7. The outer and lower edge of the wall 6 is provided with a plurality of lugs 8 which are turned over and forced into the insert 2 substantially as shown in Figure 3. In this way the insert 40 2 is prevented from slipping out of position after it has once been forced into the frame 1. The insert 2 is continuous throughout the perimeter of the frame 1 and is substantially rectangular in cross-section having a shoulder 9 and recess 10 on its upper edge which are adapted to fit within 45 the continuous shoulder 5 of the frame 1 substantially as shown. The lower edge of insert 2 is cut out to form a recess 11 and rib 12 which are also continuous throughout the perimeter of the tray. The rib 12 projects down beyond the lower edge of the 50 wall 6 and forms a seating for the tray.

The inwardly projecting flange 7 is provided with a plurality of slots 14 spaced apart so as to receive the lugs 15 which are fastened to and form a part of the bottom 3 and comprising the means for holding the said bottom in its proper position in the frame 1.

The bottom 3 is made out of a piece of sheet metal so as to compose a plurality of 60 cavities 16 which are separated by the partitions 17 and 18 which intersect one another at right angles and project upwardly and being formed out of the said bottom.

In Figure 4 I show a modification of a 70 bottom 3^a in which I provide a plurality of spaced perforations 19 into which the lugs 21 of the partitions 20 pass and removably hold the said partitions on the said bottom. This construction enables me to shift the 75 partitions so as to make any sized cavity desired. The bottom 3^a is not provided with lugs but is removable from the frame 1.

Around the edge and on the lower surface of the bottom 3 I fasten a strip of fabric 80 22 preferably of felt or wool and so situated as to rest on the flange 7 when the bottom is in place, thereby insuring a tight fit and preventing the said bottom from rattling. Likewise the bottom 3^a is provided with a 85 strip 22^a, substantially as shown.

The rib 20 is so constructed as to be U-shaped in cross-section with the walls 20^a and 20^b terminating to a plurality of downwardly projecting lugs 21, spaced apart so 90 as to fit into the perforations 19 of the bottom 3^a.

I claim:

1. A tray including in combination a 95 frame of sheet metal, a wood insert and a bottom, the inner wall of said frame forming an inwardly-projecting shoulder and terminating in an inwardly-projecting flange, the outer wall of said frame projecting downward and terminating in a 100 plurality of lugs, and the said insert having a recess on the upper inner edge to fit said shoulder and a recess on the lower outer edge to receive the said lugs of said outer wall.

105 2. In a tray, the combination of a hollow metal frame open at its lower side, a wood insert in said hollow frame having a portion projecting through said open lower side to form a seat for said tray, a ridge 110 on the upper side of said frame, and a shoulder projecting inwardly from said

ridge adapted to support the seat of a similar tray.

3. In a tray, the combination of a hollow frame including an outer wall, a ridge on the upper side adjacent to said outer wall, a shoulder at a lower level and projecting inwardly from said ridge and a support for a bottom beneath said shoulder, and a wood insert fitted in said frame against the underside of said shoulder and having a seat portion projecting below said frame.

4. In a tray, the combination of a metal frame comprising an upright outer wall terminating in a marginal ridge, a shoulder

projecting inwardly from said ridge, and a support for a bottom depending from said shoulder and a wood insert in said frame having a portion projecting below said frame to form a seat for said tray.

5. In a tray, a substantially rectangular hollow frame made in one continuous piece of metal shaped to form a shoulder and a surrounding ridge on its upper side and being open at its lower side, and a wood insert within said frame resting against the underside of said shoulder.

CAMILLE E. ROY.
